UNITED STATES PATENT OFFICE

2,068,074

REFRIGERATOR

Fay T. Rodgers, Memphis, Tenn.

Application December 20, 1934, Serial No. 758,450

1 Claim. (Cl. 62—89.5)

This invention relates to improvements in refrigerators and has especial reference to means for facilitating the exchange of heat between the refrigerator and the cooling unit or units thereof. It is primarily directed to improvements in such devices which employ a mechanical source of refrigeration though it may be adapted to ice or other types of cooling.

In refrigerators of any type, it is essential that the cooling unit take up as little space as is possible, and that it interfere as little as possible with ingress to the refrigerator, and also that it interfere as little as possible with visibility of objects therein. Probably also, it is more important that the transfer of heat from the refrigerator to the cooling unit be efficiently accomplished; that the cooling be uniformly accomplished over the entire area of the refrigerator; that accumulation of ice for the refrigerating unit be minimized and that the drip from the refrigerating unit be efficiently taken care of with a minimum of obstruction to the flow of air toward the refrigerating unit.

The objects of the present invention are,—
25 To so shape and position the cooling surfaces as to bring them into the direct line of upward flow for the air to be cooled;

To so shape the under portions of such cooling surface as to concentrate any moisture condensing thereon to a narrow area and to provide a drainage channel of such area as compared with the area of the cooling surfaces as to provide a minimum of obstruction to circulating flow of the air.

33 The means by which these and other objects are accomplished and the manner of their accomplishment will readily be understood from the following specification on reference to the accompanying drawing, in which,—

40 Fig. 1 is a longitudinal sectional elevation of a typical form of commercial refrigerator taken as on the line I—I of Fig. 2.

Fig. 2 is a transverse sectional elevation taken as on the line II—II of Fig. 1.

45 Fig. 3 is an enlarged transverse sectional elevation of a preferred form of one of the cooling units and the drain therefor, and

Fig. 4 a fragmentary corresponding front elevation of the same.

50 Figs. 5, 6 and 7 are enlarged transverse sectional elevations showing modifications of the cooling unit and drain shown in Fig. 3.

55 Referring now to the drawing in which the various parts are referred to by numerals, 10, 11,

12 and 13 are respectively the end, top, bottom and front walls of the refrigerator, and 14 the doors through which access is had to the rear of the refrigerator. 15 and 16 indicate the usual shelves on which merchandise is displayed. 5

The cooling units include an elongated group of pipe coils 20 which are disposed in a generally horizontal bank in the upper portion of the refrigerator and extend substantially from end to end thereof, and preferably also an additional 10 similar group or groups as the coils 21 disposed immediately below the shelf 15. These coils are cooled in usual manner as by the expansion of ammonia gas, carbon disulphide, or other refrigerant gas. 22 indicates a compressor-condenser unit, 23 piping connecting the condenser and coils, and 24 the return pipe from the coils to the compressor.

Each group of coils is housed in a shallow 20 housing 30, 31 respectively, these housings being filled with a liquid as oil, salt water or other liquid which will not freeze at refrigerating temperatures. In their preferred form each housing has a substantially flat top 32, shallow sides 33, and ends 34, and a bottom 35 sloping slightly 25 downward from the two side walls 33 to the center. The width of the housing is slightly less than the depth from front to back of the refrigerator, with which it is to be used, and is usually only slightly greater than the overall 30 width of the bank of coils with which it is used, though this is not essential since heat transference is accomplished through the liquid filling the housing. The depth of the housing is pref- 35 erably only sufficient to readily accommodate the bank of coils. The slope of the bottom of the housings is slight and is only such as is necessary to cause moisture condensing thereon to drain toward the midpoint. Immediately below the 40 junction of the two portions 35 of the bottom, is a substantially horizontal channelway 40 which for economy and strength may be an angle iron. From this channelway, drain pipes 41 at opposite ends of the refrigerator case lead downward, 45 and if necessary to avoid a lower shelf or housing, backward and discharge in the bottom of the refrigerator case.

In some instances it may be more satisfactory to arrange transversely sloping groups of coils 50 20A and to conform the slope of the top 32A as well as the bottom 35A of the housing to the slope of these banks of coils. Where two such banks of coils are used they may be arranged as shown in Fig. 5, and a single channel 40A 55

take care of the drainage of both housings. In Fig. 6, three groups of coils 20B, and a corresponding number of housings 30B and channels 40B are shown.

5 In Fig. 7 the coils 20C are banked in one flat group, the top and bottom of the housing 30C are shown parallel and a single channel 40C is used.

In using the cooling system a refrigerant such 10 as carbon di-sulphide is pumped into the coils by usual apparatus, under usual control, and allowed to expand in usual manner. The warmer air in the refrigerator flows directly upward against the underside of the housing 30 and is 15 directly cooled thereby. Any moisture contained in the air is distributed over a long, broad surface, and any tendency to form a coating of ice of an insulating thickness is definitely minimized. Any moisture which forms on the surfaces during 20 defrosting or at any other time, is led along the underside of the housing by capillary attraction, and is carried off by the drain channel 40 under the low point thereof.

It will clearly be seen that the drain channel 25 40 is shown, and can be made, of such restricted width as compared to the total width of the housing that it will offer a minimum obstruction to the flow of the warm air against the cooling surface. It will further be seen that surfaces of the

cooling unit are smooth and can be readily cleaned at any time.

What I claim is:

A refrigerator including an elongated casing having an article supporting shelf therein, and 5 cooling means in said casing spaced above said shelf, said casing having a glass front extending from the under surface of the top of said casing substantially to the level of said shelf; said means comprising a flat coil of pipe, means for circulating a cooling medium through said coil; an elongated flat housing enclosing said coil, said housing being substantially horizontally disposed, having smooth exterior surfaces and an under- 10 surface sloping to a longitudinally disposed drain- 15 age line, a heat transference medium in said housing surrounding said coil; and a drain disposed along and below the drainage line of said housing, said housing lying adjacent said casing top but being unobstructedly spaced from the contiguous 20 surface to permit access for cleaning, the front portion of said housing closely embracing the coil therein whereby to minimize the thickness of said front portion, and said drain being spaced rear- 25 wardly from said front, whereby to present a minimum obstruction of vision to articles on said shelf.

FAY T. RODGERS.
